UNITED STATES PATENT OFFICE!

JOHN H. SETSER, OF DECATUR, ARKANSAS.

ROTARY ENGINE.

No. 863,324.

Specification of Letters Patent.

Patented Aug. 13, 1907.

Application filed September 13, 1906. Serial No. 394,519.

To all whom it may concern:

Be it known that I, JOHN H. SETSER, a citizen of the United States, residing at Decatur, in the county of Benton, State of Arkansas, have invented certain new and useful improvements in Rotary Engines; and I do hereby declare the following to be a full, clear, and exact description of the invention, such as will enable others skilled in the art to which it appertains to make and use the same.

10 This invention relates to rotary engines and more particularly to that class including a two-part casing in which is mounted a wheel carrying a plurality of piston heads against which, steam, from a supply pipe impinges and the primary object of the invention is 15 to provide an improved structure of this class which will be easy running and which will comprise but few parts which may be readily disassembled for cleaning or for repair.

Furthermore the invention resides in the provision 20 of a wheel or disk having piston heads of novel construction.

In the accompanying drawings,—Figure 1 is a side elevation of a rotary engine constructed in accordance with my invention. Fig. 2 is a plan view thereof. 25 Fig. 3 is a detail vertical transverse sectional view through the same. Fig. 4 is a detail perspective view of a portion of the disk carrying the piston heads, several of the piston heads being also shown in perspective, and Fig. 5 is a view similar to Fig. 3 showing 30 a slightly modified form of my invention.

Referring more specifically to the drawings there is shown a base frame including spaced sills 5 and 6, the sills 5 being designed to support the engine proper and the sills 6 being provided with bearing box 7 for 35 the engine shaft.

The engine proper comprises a casing formed of a pair of sections 8 which are identical in construction and which are each in the form of a disk having formed therein an annular semi-cylindrical channel 9 which 40 is located adjacent the outer edge of the disk, the said channel forming, when the sections are connected, a continuous cylinder. That portion of each disk which lies outwardly of the channel formed therein serves as a flange 10 by means of which sections may 45 be secured together there being a plurality of bolts 11 engaged through the said flange for the purpose stated.

The web portions of the members, or in other words that portion of each member which lies inwardly of 50 the channel, are in spaced relation with respect to each other and received between the web portions is a disk 12 which carries upon its periphery a plurality of piston heads 13 which are formed integral with the disks and which are concavo-convex in form, it being

understood that the said piston heads move in the 55 continuous cylinder formed by the channels 9 in the cylinder members. To brace the connection of the piston heads with the disk 12, the said heads are gradually thickened as they approach the periphery of the disk as indicated by the numeral 13' and the 60 lower edge of the rear face of each piston head terminates at the lower edge of the forward face of the next adjacent piston head in rear of the one mentioned.

The numeral 14 denotes the engine shaft which is engaged through an opening formed centrally through 65 the disk 12, the said disk being fixedly secured to the shaft and being secured to the flare at this point as at 15.

An opening 16 is formed through the disks 8 at the point corresponding to the opening in a disk and 70 the wheels of the opening 16 are tapered to receive the flared portion of the said disk 12, and hence the edges of the opening in the disks 8 through which the shaft 14 is engaged, do not contact with the shaft.

In order that the engine may be mounted fixedly 75 upon its supporting frame, pairs of attaching brackets 17 are formed upon opposite sides of the cylinder of the engine at corresponding points in a plane slightly beneath that occupied by the engine shaft 14 and the engine is secured by means of the said brackets and 80 85 sills 5 engaged therethrough upon the sills 5.

A steam inlet pipe 18 communicates with the continuous cylinder, formed by the annular channels 9, adjacent the top of the engine casing and slightly to one side of the connecting flange for the sections thereof, and a steam outlet pipe leads from a corresponding point adjacent the lower end of the casing.

In the form of my invention shown in Fig. 5 the sections comprising the casing of the engine instead of being provided with semi-cylindrical channels 90 are provided with annular grooves of such construction that when the sections are connected continuous rectangular passage way is formed and serves as the cylinder of the engine and in this form hollow pyramidal piston heads 20 are employed. 95

What is claimed is:—

An engine of the class described comprising a casing having a continuous cylinder, a disk mounted for rotation in the cylinder, and concavo-convex piston heads carried by the disk, said heads having their convexed faces extended to the concave face of the next adjacent rearward blade and being thickened at their base or point of connection with the disk. 100

In testimony whereof, I affix my signature, in presence of two witnesses.

JOHN H. SETSER.
